UNITED STATES PATENT OFFICE

160,652

BATHROOM FIXTURE

Lionel Ouellette, Lawrence, Mass.

Application April 3, 1950, Serial No. 8,944

Term of patent 14 years

(Cl. D4—3)

To all whom it may concern:

Be it known that I, Lionel Ouellette, a citizen of the United States, residing at Lawrence, in the county of Essex and Commonwealth of Massachusetts, have invented a new, original, and ornamental Design for Bathroom Fixture, of which the following is a specification, reference being had to the accompanying drawing, forming part thereof.

Fig. 1 is a front elevational view of a bathroom fixture showing my new design, the doors thereof being in opened position;

Fig. 2 is a top plan view of Fig. 1; and

Fig. 3 is a perspective view of my bathroom fixture with the cabinet doors and toothbrush compartments in closed position.

I claim:

The ornamental design for a bathroom fixture, as shown.

LIONEL OUELLETTE.
